UNITED STATES PATENT OFFICE.

HOWARD H. HAHN, OF DENVER, COLORADO, ASSIGNOR TO THE WESTERN ENGINEERING COMPANY, OF DENVER, COLORADO.

WALL-MOLD.

No. 856,952.

Specification of Letters Patent.

Patented June 11, 1907.

Application filed February 13, 1905. Serial No. 245,384.

To all whom it may concern:

Be it known that I, HOWARD H. HAHN, a citizen of the United States, residing at the city and county of Denver and State of Colorado, have invented certain new and useful Improvements in Wall-Molds; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 My invention relates to improvements in wall molds consisting of a device whereby a wall may be formed in place without the necessity of constructing it of pieces or blocks.

20 My improved device makes it practicable to complete a wall as a continuous structure, the mold being clamped to the wall and movable both vertically and horizontally. It is so constructed as to form a certain portion of the wall at each molding act, the size of the 25 parts so formed depending on the size of the mold. After the one molding act is completed, the device may be unclamped and moved vertically or horizontally, when the 30 operation is repeated. In this way a wall 35 of any size or length may be formed of suitable material as cement concrete.

The device consists of a mold formed of two members connected by suitable devices whereby the members may be clamped in 35 place during the formation of a portion of the wall.

It further consists of a core for use in connection with the mold, in order that the wall may be formed hollow or provided with cavities at suitable intervals. This core is preferably composed of two adjustable members whereby it may be loosened and withdrawn from its position in the wall at pleasure.

Having briefly outlined my improved construction as well as the function it is intended to perform, I will proceed to describe the same in detail reference being made to the accompanying drawing in which is illustrated an embodiment thereof.

50 In this drawing, Figure 1 is a perspective view illustrating my improved wall mold in position for use. Fig. 2 is an end view of the same the mold and wall being shown in section. Fig. 3 is a side elevation of the mold

shown in detail and partly broken away. Fig. 4 is an end view in detail illustrating the mold which is shown partly in section. Fig. 5 is a side elevation of the core. Fig. 6 is a section taken on the line 6—6 Fig. 5. Fig. 7 is a top plan view of the core.

The same reference characters indicate the same parts in all the views.

Let 5 5 designate the members of my improved mold. These members may be formed of any suitable material as wood. They consist of sides 6 6 connected in any suitable manner and provided with interior walls 7. At each extremity of each side 6, is located a post 8. To the top of each post 8 is attached a nut 9 in which is threaded a shaft 10 or rod 10 provided with right and left threads engaging the nuts 9. In the center of the shaft 10 is located a hand wheel 12 for manipulating the shaft. Each post is also provided with an additional nut 13 secured both to the post 8 and the top of the sides 6 by means of suitable bolts. In these nuts 13, are also threaded screw shafts 14 provided with right and left threads engaging the respective nuts 13. The shaft 14 is also provided with a hand wheel 15. The shafts 10 and 14 and their hand wheels are substantially identical but they are given different reference characters for convenience of description. The posts 8 at each end of the structure are substantially the same and are connected in the same manner. The screw shafts 10 and 14 at each end of the device, form means for clamping the mold members to the wall and also means for loosening the clamped members when it is desired to move the mold from one position to another. Each side 6 of the mold as shown in the drawing is braced by tie rods 16.

The construction of the core used in connection with the mold for forming recesses in the wall at suitable intervals will now be described. This core may be designated in its entirety by the numeral 17. As shown in the drawing it consists of two members having side walls 18 and overlapping ends 19. Each of these walls is provided at the top with two ears or metal projections 20 in which are threaded screws 21 provided with right and left threads at their opposite extremities. In the center of each screw is located a hand wheel 22 to facilitate the manipulation of the screws. Near the lower

part of the two members 17 and on the inside is located a spacing plate 23 which is hinged to one of the sides as shown at 24. Its extremity remote from the hinge 24 is 5 pivotally connected with a vertically slideable rod 26 engaging eyes 27 formed on the inside of the opposite side member 18. This rod 26 passes through a metal part 28 at the top of the side member. To the upper extremity of this rod which is threaded for the purpose is applied a thumb nut 29 to facilitate vertical adjustment. From this description it will be seen that there are two screws 21 located at the top of the core for purposes of 15 adjustment, while the spacing plate 23 is centrally located between the screws, and at the lower part of the device on the inside. By means of the screws and the spacing plate, the sides of the core may be so adjusted that 20 they are parallel with each other.

From the foregoing description the use and operation of my improved device will be readily understood. Assuming that a base designated 30 in Fig. 2, is formed, the same 25 being of somewhat greater thickness than the thickness of the wall proper, the members of my improved mold may be placed thereon and regulated so that the space between the sides shall correspond with the 30 thickness of the wall. The core is then placed in position between the sides, after which the material of which the wall is to be composed, is introduced until the space between the sides of the mold and surrounding 35 the core 17 is filled. After this is sufficiently dry to warrant the removal of the core in the mold, the core is adjusted so as to make it somewhat smaller whereby it may be easily raised from its cavity in the wall. After it 40 has been elevated a suitable distance but not

entirely out of the said cavity, the screws and the vertical rod are adjusted to maintain it in position. The mold members are then adjusted to allow them to be raised, after which they are again tightened by 45 means of the screw shafts upon the wall, when the operation of molding another section of wall is repeated. In this way the matter may be carried on indefinitely.

Having thus described my invention, what 50 I claim is:

1. A wall mold consisting of two side members, suitable clamping devices connecting the side members whereby they may be securely connected with the wall, and a core 55 interposed between the side members and consisting of two distinct parts, screws provided with right and left threads connecting the core parts, and a spacing plate hinged to one part, a rod connected with said plate and 60 vertically slideable on the other core part, and a nut also applied to the rod to adjust the latter and operate the spacing plate, substantially as described.

2. A core for molds consisting of two distinct members, screws provided with right and left threads connecting the members, and a spacing plate hinged to one member, a rod connected with the plate and vertically 65 slideable on the other member, and a nut also applied to the rod member, to adjust the latter and operate the spacing plate, substantially as described.

In testimony whereof I affix my signature in presence of two witnesses.

HOWARD H. HAHN.
